PAGE 11

FIG.14.

FIG.15.

This is a continuation of United States applications Serial No. D. 60,375, filed April 29, 1960; Serial No. D. 60,378, filed April 29, 1960; Serial No. D. 60,377, filed April 29, 1960; Serial No. D. 63,701, filed January 25, 1961; Serial No. D. 63,702, filed January 25, 1961.

I claim:

The ornamental design for a grille, substantially as shown and described.
